UNITED STATES PATENT OFFICE.

GEORGE W. CISCO, OF HAWTHORNE, NEW JERSEY, AND JOHN F. MACKAY, OF LANCASTER, PENNSYLVANIA.

INCUBATOR.

Application filed August 18, 1920, Serial No. 404,289. Renewed June 25, 1925.

To all whom it may concern:

Be it known that we, GEORGE W. CISCO and JOHN F. MACKAY, citizens of the United States, residing, respectively, at Hawthorne, in the county of Passaic and State of New Jersey, and Lancaster, in the county of Lancaster and State of Pennsylvania, have invented certain new and useful Improvements in Incubators, whereof the following is a specification, reference being had to the accompanying drawings.

Our invention relates to incubators, and is more especially concerned with provisions for heating them and for regulating their temperature, and controlling air circulation through them. The invention is also concerned with multi-decked incubators, and particularly with provisions for their construction in stacked sections and for obviating undesirable influence of an incubator section or chamber on the temperature or the atmospheric conditions of associated sections or chambers. How these and other advantages can be realized through the invention will become readily apparent from the detailed description which follows.

Fig. I is a front elevation of a sectional incubator structure conveniently illustrating my invention, a portion thereof being shown in section to set forth certain important details to better advantage.

Fig. II is an elevation of the right hand end of the incubator.

Fig. III is a view on an enlarged scale, partly in elevation and partly in section, of one of the incubator units showing also a portion of an adjacent unit superimposed upon the first, and the means by which the two are held from relative displacement.

Fig. IV is a cross sectional view along the plane of the arrows IV—IV in Fig. III.

Fig. V is a detail view in section.

Fig. VI is a diagrammatic perspective view of a structure comprising two columns of sectional incubator units such as shown in Figs. I and II, arranged back to back.

Fig. VII is a detail view in section, showing a simple method by which the corresponding pipes in adjacent sectional units may be united.

The organization represented in Figs. I and II, it will be observed, comprises a multiplicity of sectional units respectively designated by the numeral 1. These, as is clearly shown, are stacked or superimposed

one upon another, so that the structure as a whole has a compact, cabinet like appearance. As will become apparent from further description, the sectional units 1, and likewise the top 2 and base 3, are so made as to be interchangeable in order to permit re-arrangement, and so that additional units may be readily added from time to time if it is desired to increase the capacity of the structure, without necessity of any alterations whatever in any of its constituent parts. Such sectional units may in themselves comprise any number of separate incubation chambers, but for the purposes of illustration in the present connection, we have shown them in Figs. III and IV as comprehending but two of such chambers 5—5 which are preferably arranged side by side. In practice, we prefer to limit the sectional units to a size such that they may be readily crated and shipped completely assembled. The end walls 6—6, the back 7, and the intermediate partition 8 in each section are made hollow to afford thermo insulating air spaces, and the closure is completed by top and bottom boards 9 and 10 respectively. At the ends of the bottom of each sectional unit are projections formed by attached transverse battens 11, which, together with a central batten 12 serve to space the unit from the one next below it, as clearly shown in Fig. III, thus providing between adjacent units, horizontal thermo-insulating spaces or passages 13 through which air may readily flow, and thereby prevent cross radiation between the various separate incubation chambers comprised in the structure. To the tops of the sectional units are secured battens 14 which are so disposed as to serve as correlative projections and cooperate with the end battens 11 in preventing endwise displacement between adjacent units when set one upon the top of the other as shown. The battens 14 of each unit terminate at their ends a trifile short of the front and rear of the sectional units to which they are attached so as to be overlapped by projections consisting of the lower edges of the face rails 15 and the back boards 16 of the adjacent superimposed unit, the interlock thus established serving to prevent sidewise displacement between adjacent superposed units. The rails 15 and boards 16 are cut away as at 17, 17 to provide openings which communicate

105
110

with the spaces 13 previously referred to. As clearly shown in Fig. I, the top 2 and the base 3 are held from displacement by battens 11 and 14, similar to those already 5 described.

By thus standardizing the constituent units of the structure, it will be apparent that they may be readily interchanged, or new sections added from time to time to increase 10 capacity, while assemblage is maintained without the aid of any special securing means. It is also obvious that the compactness of the structure, built up in the manner above set forth, admits of greater 15 conservation of space than has heretofore been possible in incubators of large capacity.

The chambers 5—5 are closed at the front by doors 20, which are hinged at their lower edges as indicated at 21—21 so as to be 20 swingable downwardly. The door of each horizontal row or tier may be thus actuated by mechanism which includes, in each instance, a horizontal shaft 22 bent at one end into the form of an operating crank 23 25 (Figs. I and II), and having attached to it lever arms 25, which are connected by interposed links 26, with resiliently flexible connectors 27 secured to the doors 20. The cranks 23 are normally locked by means of 30 hooks 28 (Figs. I and II) in such positions as to induce in the flexible connectors 27 sufficient pressure to hold the doors 20 normally closed. By the arrangement just described, the doors in each sectional unit may 35 be simultaneously opened to afford access to the interior of the various incubation chambers comprised in it.

Within each incubation chamber at a 40 plane intermediate of its height is mounted an egg tray 30 which may be of any appropriate construction. These trays are preferably supported in horizontal slide-ways so that they may be projected from within the chambers to permit the occasional 45 airing of the eggs which, as is well known, is essential during the incubation period. Proper humidification of the air within the various incubation chambers is obtained by provision of the usual moisture pans shown 50 at 31. Each sectional unit is heated by a bank of hot water pipes 32 which are common to its several incubation chambers and which run longitudinally through their very tops, so that radiation is obliged to take 55 place downwardly through the egg trays 30. The ends of the pipes 32 project beyond the sectional units and are threaded as at 33—33, so that they may be connected in various ways to establish a closed hot water circulatory system. Each incubation chamber 60 has at its rear one or more fresh air inlet openings 35, and at its front an outlet opening 36. These openings 35 and 36, as will be best seen from Fig. V, are diagonally opposite each other and respectively dis-

posed in close proximity to the bottom and top of the chamber so as to predetermine upward circulation of the air therein, counter-wise to that of the heat radiation from the pipes 32. The airflow is broken 70 up or dissipated, as suggested by the arrows in Fig. IV, in passing through the egg tray, so that thorough distribution is assured. The efflux through the discharge opening 36 is governed by a throttle valve 37 pivoted 75 centrally within an outlet 38 which registers with said opening. The throttle 37 is automatically controlled according to the temperature existing in the chamber by means of a thermostat 39 which is secured 80 to a bracket 40 extending rearwardly from the outlet 38, and which through a lever 41 is connected to an adjustable link 42 to actuate the counter-weighted arm 43 which is in turn connected by a link 44 to a downwardly turned end 45 of the pivot rod 46 of the throttle valve. A stop 47 serves to limit the movement of the throttle to the full open position shown in Fig. V. Under the principle of air circulation outlined above, 85 it will readily be seen that the bottoms of the eggs are maintained at a lower temperature than their tops thus imitating more closely the natural conditions of hatching 90 under the hen.

In Fig. VI, we have shown in perspective two column structures set up after the manner of Fig. II and arranged back to back, this method of compounding admitting of 100 economical operation from a common source of hot water supply as will be presently explained. According to the illustration, the ends of the vertically corresponding pipes 32 of the banks in the several units, shown in 105 dotted lines in the right hand incubator section column of the structure, are interconnected alternately at their opposite ends by connectors 50, and the upper terminals of each adjacent pair of the vertical zig-zag 110 courses thus established in turn connected by connectors 51. By this arrangement, these vertical courses serve alternately as flow and return units. The lower terminals of the alternate vertical courses are connected, respectively, to manifolds 53 and 54, 115 which, through pipes 55 and 56, communicate with a water heater conventionally represented at 57; and thus there is formed a double closed circulatory system (of two parallel circuits) adapted for operation by 120 convection. The pipe banks in the incubator section column at the left of the figure are connected in a manner similar to that just described, so that the two are in 125 perfect balance and the circulation throughout the entire system is rendered absolutely uniform. Thus the pipe bank 32 of each incubator section has closed circuit circulatory connections to its inlets and outlets 130 at 33; and the vertical flow and return

courses of the system extend side by side through the several chambers from top to bottom of the incubator structure. The system is provided with vents 52, 52, to allow 5 for expansion of the heating medium in a manner well understood. We prefer to make the connections between the various pipe banks as shown in Fig. VII simply by use of two short nipples 58, 58, united by a 10 union 59.

The characteristics of this heating system will be best understood by the illustrative example which follows:

Let it be assumed that a temperature of 15 100° F., is to be maintained within the several sectional units of the structure, and that a drop of 1° F., takes place in transition of the heating medium from one pipe bank to the next succeeding. Accordingly the temperature of the flow pipes of the lowermost 20 unit of a five tier structure as herein represented must be 104° F., and by similar reasoning, the return 96° F. In the section next above, the flow will be 103° F. and the 25 return 97° F., and so on, while in the uppermost section, the flow and the return will have the same temperature value of 100° F. By averaging the two figures in each instance, it will be seen that by relative compensation, a uniform effective temperature of 100° will be obtained.

Having thus described our invention, we claim:

1. A sectional incubator comprising a 35 multiplicity of superposed, interchangeable, chambered unit sections each having at both top and bottom spacing and engagement means correlative adapted to interlock with those at bottom or top of an adjacent 40 section and to space the sections apart so that their top and bottom walls shall form a double wall partition with narrow air spaces therein, and each also having therein a horizontal bank of radiating pipes with 45 inlet and outlet connections to the exterior of the section for circulation of a heating medium through said pipes.

2. A chambered incubator unit section having closed top and bottom walls with, 50 in the one case, projections extending at right angles at each corner, and, in the other case, correlative projections adapted to engage in the angles of said first mentioned projections on another such section and 55 thereby interlock the sections in definite relative positions one on the other, the sections being slightly spaced apart by their projections to afford a narrow thermo-insulating air space between them.

3. A chambered incubator section adapted 60 for stacking with similar sections and having in its chamber an egg tray at a level intermediate of its height; a bank of heating pipes in the top of said chamber freely exposed to radiate directly downward on the

tray; air inlet and outlet passages at opposite sides of said chamber, beneath and above said tray, respectively; and a thermostatic damper for the air outlet passage completely controlling influx of air to the chamber and circulation of air therethrough. 70

4. A chambered incubator section adapted for stacking with similar sections and having a closed top wall, and an egg tray at a level intermediate of its height; a bank of 75 heating pipes in the top of its chamber; air inlet and outlet openings beneath and above said tray, respectively, the latter in a side wall of the chamber; and thermostatic damper mechanism for the air outlet beneath said top wall completely controlling influx of air to the chamber and circulation of air therethrough.

5. A chambered incubator section adapted for stacking with similar sections and having closed top and bottom walls with spacing and engagement means correlative adapted to interlock with those of adjacent sections, and space the sections apart to afford thermo-insulating spaces between them; 85 an egg tray in its chamber at a level intermediate of its height; a bank of heating pipes in the top of said chamber; air inlet and outlet passages at opposite sides of said chamber, beneath and above said tray, respectively; and a thermostatically controlled damper directly responsive to the temperature beneath said heating pipes and completely controlling influx of air to the chamber and circulation of air therethrough. 95

6. A sectional incubator comprising a multiplicity of interchangeable, superposed chambered sectional units provided with individual banks of horizontally disposed heating pipes which protrude to the exterior 105 beyond the ends of the sectional units to permit of their being interconnected with each other or with corresponding pipes of adjacent units.

7. An incubator comprising a plurality of 110 superposed incubation chambers, including a chamber below the upper one having a closed top wall and an egg tray at a level intermediate of its height, a bank of heating pipes in the top of said chamber, air inlet and 115 outlet openings beneath and above said tray, the latter in a side wall of the chamber, and thermostatic damper mechanism for the air outlet beneath said top wall completely controlling influx of air to the chamber and 120 circulation of air therethrough.

8. An incubator comprising an incubation chamber with an egg tray at a level intermediate of its height, a bank of heating pipes in the top of said chamber freely exposed to radiate directly downward on the tray, air inlet and outlet passages at opposite sides of said chamber, beneath and above said tray, and a thermostatic damper for the air outlet passage completely con- 125

130

trolling influx of air to the chamber and circulation of air therethrough.

9. An incubator structure comprising a multiplicity of incubation chambers arranged in superimposed relation; in combination with a heating system including individual banks of heating pipes for said chambers, the corresponding pipes in the several banks being connected in vertical sequence at alternate ends of the structure, and adjacent pairs of the vertical zig-zag courses thus established being interconnected at their upper ends and communicating at their lower ends with inlet and discharge manifolds respectively, so that said vertical courses serve alternately as flow and return units.

10. An incubator structure comprising a plurality of superposed incubation chambers, and a closed circuit heating system therefor comprising flow and return courses extending side by side through the various incubation chambers from top to bottom of the incubator, so that by connecting the flow

and return courses to the delivery and return sides of a heater a closed heating circuit will be established and all the chambers heated uniformly.

11. In an incubator structure comprising a plurality of superposed incubation chambers, a closed circuit heating system therefor comprising flow and return courses extending side by side through the various incubation chambers from top to bottom of the structure, the corresponding pipes in each course being detachably coupled together in vertical sequence at alternate ends, and the ends of the flow and return courses being connected to the delivery and return sides of a heater, so as to form a closed heating circuit and heat all the chambers uniformly.

In testimony whereof, we have hereunto signed our names at the city of Paterson, New Jersey, this fifth day of August, 1920.

GEO. W. CISCO.
JOHN F. MACKAY.
